UNITED STATES PATENT OFFICE.

WILLIAM J. SMITH, OF WATERBURY, CONNECTICUT.

SEPARABLE FASTENER.

1,251,831.

Specification of Letters Patent.

Patented Jan. 1, 1918.

Application filed July 2, 1917. Serial No. 178,232.

To all whom it may concern:

Be it known that I, WILLIAM J. SMITH, a citizen of the United States, residing at Waterbury, in the county of Waterbury, 5 State of Connecticut, have invented certain new and useful Improvements in Separable Fasteners; and I do hereby declare the following to be a full, clear, and exact description of the invention, such as will enable 10 others skilled in the art to which it appertains to make and use the same.

This invention relates to separable fasteners.

The object of the invention is to provide 15 a separable fastener which is particularly adapted for use upon carriage and automobile curtains, and heavy goods of various kinds. In carrying out the invention it is intended to provide a button having a secure mounting, by which the fabric is evenly held and the strain thereon is evenly distributed.

Furthermore, it is the object of the invention to provide a fastener of neat appearance, and one capable of suitable ornamentation and finish.

With the above objects in view, and such others relating to the details of construction, as may hereinafter appear, my invention 30 will now be fully set forth and described, reference being had to the accompanying drawings.

In the drawings:—

Figure 1 is a view of the device in use,

Fig. 2 is a rear view thereof,

Fig. 3 is a rear view of the device removed from the fabric,

Fig. 4 is a view of the device with the back plate removed, and

Fig. 5 is a section through the device in its applied position.

Referring more particularly to the drawings, 1 represents a cap plate or body which has an annular flange 2 and a central depression or dome 3. The annular flange 2 provides a seat which confines a spring retaining member 4. The spring retaining member 4 consists of an annulus 5 which is expanded against the flange 2, and a pair 45 of arms 6 which extend across the base of the dome 3 in spaced and slightly divergent relation. Crimped or otherwise secured within the edge of the flange 2 is a closure plate 7 which has a socket opening or recess 8 registering with the dome 3 and is

furthermore surrounded by an outwardly turned flange 9. Also, the closure plate 7 is provided with a plurality of prongs 10 which are adapted to grip into the fabric to which the fastener is secured. 60

A securing plate 11 which is a centrally apertured disk, is provided to be received over the flange 9 and upon the inner face of the fabric, the edge of the flange being then overturned or crimped to secure the 65 plate in position and properly clamp the fabric, the prongs 10 entering the goods or fabric to prevent relative rotation of the fastening device.

The socket member thus provided is 70 shaped to receive the complementary male member 12, the latter being a headed projection having an annular groove which will receive the spring arms of the resilient member 4. The head of the member 12 is so 75 shaped that it may readily pass between the sides of the spring retaining member, until the latter snap into the annular groove, and the conformation is furthermore such that the arms of the spring member may be 80 sprung apart by pulling upon the separable members of the fastener. If desired, the face of the plate 1 may be apertured adjacent the contracted portion of the spring 85 arms of the retaining member, so that if it is necessary, an instrument may be inserted therebetween to assist in the operation of the members, should they fit together too tightly.

It will be apparent from the foregoing 90 description that I have provided a very simple and effective separable fastener which is equally adapted for use on automobile or other vehicle curtains, or upon uniforms and heavy garments. The form of 95 the headed or male member is shown adapted for insertion in a vehicle body, but it is obvious that a different form of attaching device may be supplied without departing from the spirit of my invention. 100

What I claim as my invention is:—

A separable fastener, comprising in combination, a socket member comprising a comparatively wide plate having a dome rising from its center, a flange on the plate extending in the opposite direction to said dome, a spring retaining member contacting said flange throughout its inner surface and having resilient arms extended across the dome, a plate apertured to register with the con- 105

110

cavity of the dome and secured within the free edge of the flange surrounding the first mentioned plate so as to secure said spring retaining member, an annular outwardly directed flange surrounding the aperture in the last mentioned plate, a plurality of prongs projected from the outer face of the second mentioned plate, and a securing plate centrally apertured to receive said annular

flange and to have the latter swaged there- 10 over.

In testimony whereof, I affix my signature in the presence of two witnesses.

WILLIAM J. SMITH.
